SCRATCHER FOR WELL BORES

James S. Gassaway, Los Angeles, Calif., assignor
to Baker Oil Tools, Inc., Vernon, Calif., a corporation of California

Application June 1, 1951, Serial No. 229,360

13 Claims. (Cl. 166—173)

1

The present invention relates to subsurface well tools, and more particularly to devices for scratching or scraping the walls of open well bores, conduits of various kinds disposed in well bores, and the like.

An object of the present invention is to provide improved scratcher devices that are capable of effectively removing mud cakes and other undesired substances from the walls of well bores and well conduits disposed in well bores.

Another object of the invention is to provide scratcher devices embodying wall engaging spring elements that can be assembled with facility on their supporting members, and with the employment of a minimum number of parts and operations.

A further object of the invention is to provide a scratcher device that lends itself to production through the use of automatically operating equipment, thereby decreasing substantially the cost of manufacturing the devices and the time consumed in producing them.

Yet another object of the invention is to provide scratcher devices embodying wall engaging spring elements and supporting members therefor, in which the spring elements and supporting members maintain themselves in appropriate assembled relation with respect to each other, without the need for any other parts or materials.

Still a further object of the invention is to provide a scratcher device embodying wall engaging spring elements that can contain more spring coils, thereby making the elements more flexible for the performance of their wall scratching function, and less susceptible to permanent distortion.

Another object of the invention is to provide a scratcher device for use in a well bore that is of stronger and sturdier construction, and in which the looseness or play between the spring elements and their supporting member can be varied, and, if desired, substantially completely eliminated.

This invention possesses many other advantages, and has other objects which may be made more clearly apparent from a consideration of a form in which it may be embodied. This form is shown in the drawings accompanying and forming part of the present specification. It will now be described in detail, for the purpose of illustrating the general principles of the invention; but it is to be understood that such detailed description is not to be taken in a limiting sense, since the scope of the invention is best defined by the appended claims.

Referring to the drawings:

2

Figure 1 is a side elevation of a wall scratcher mounted on a casing section, with parts being disclosed in longitudinal section;

Fig. 2 is a cross-section taken along the line 2—2 on Fig. 1;

Fig. 3 is a somewhat diagrammatic view of a wall scratcher mounted on a casing string during lowering of the latter in a well bore;

Fig. 4 is a view similar to Fig. 3, disclosing elevation of the casing string and scratcher in the well bore;

Fig. 5 is an enlarged plan view of a portion of a wall scratcher device prior to complete assembly of the scratcher elements on their supporting collar or sleeve;

Fig. 6 is an enlarged fragmentary section taken along the line 6—6 on Fig. 5;

Fig. 7 is an enlarged fragmentary section taken along the line 7—7 on Fig. 5;

Fig. 8 is a plan view of one of the scratcher elements;

Fig. 9 is a rear elevation, disclosing the mounting of one of the scratcher elements in the supporting member or sleeve.

As disclosed in the drawings, a wall scratcher A is mounted on a casing section B, for the purpose of removing the mud cake C from a portion of a well bore D in which the casing string is to be disposed, and also to center the casing string in the well bore. The scratcher has the primary purpose of removing the mud cake or sheath C from a particular portion of the well bore, in order to insure a proper bond between the formation wall and cement slurry, or other cementitious material, pumped down the casing string B for upward passage through the annulus E around the latter. It is preferred not to disturb the mud cake in the well bore to any substantial extent, except along that portion of the formation wall at which the cementitious material is to be disposed. For that reason, the wall scratcher A should engage the mud cake lightly, if at all, during descent of the casing string through the well bore. However, the scratching effectiveness should be at a maximum during upward movement of the scratcher in the well bore.

The wall scratcher A could be firmly secured to the casing string B, but it is preferred to provide for its slidable movement thereon. Thus, the wall scratcher includes a supporting collar or sleeve 10 slidable on a casing section B and adapted to engage stop elements 11, 12, such as ring members, welded to the casing section on opposite sides of the scratcher. These stop elements 11, 12 may be disposed a few feet apart.

During downward movement of the casing string B in the well bore D, the upper stop element 11 will engage the collar 10, forcing the scratcher device downwardly through the well bore. Slight upward movement of the casing string, such as occurs in lifting it out of the rotary table slips (not shown) at the top of the well bore, will not move the scratcher device A in an upward direction, inasmuch as the lower stop element 12 will not engage the lower end of the collar 10 during such slight upward movement. Greater upward movement, however, will engage the lower ring 12 with the collar and move the scratcher device A upwardly with the casing string B.

The collar 10 has an outwardly directed bead portion 13 formed in it provided with two longitudinally spaced rows 14, 15 of circumferentially spaced apertures or holes. The holes of each row are preferably equidistant from each other and the holes in one row 14 are circumferentially offset with respect to the holes 15 in another row. Scratcher elements 16 are insertable through the rows of holes, each element being retained in appropriate assembled position on the collar or sleeve 10, with the finger portions 17, 18 of each scratcher element extending outwardly of the collar or sleeve 10 to a substantial extent.

As seen most clearly in Fig. 8, each scratcher element 16 includes an intermediate, generally U-shaped heel or base portion 19, the spaced arms 20 of which merge into coil portions 21 extending in opposite and outward directions from the base portion 19. Each coil portion 21 consists of a plurality of turns, the outer parts of which merge into the elongate wire fingers 17, 18. As disclosed in Fig. 8, each finger includes an inner portion 22 integral with the coil 21, and an outer portion 23 of substantial length which may be bent transversely in an outward direction with respect to the inner portion 22, to provide a pair of outwardly diverging elongate finger portions 17, 18.

Each scratcher element 16 is mounted on the cylindrical collar or sleeve 10 from the interior thereof. It is to be noted that the U-shaped heel or base portion 19 of each element 16 is disposed at an angle to the finger portions 17, 18, as disclosed in Figs. 6 and 7. Each element 16 is inserted through selected holes in the rows 14, 15 of apertures formed in the bead 13, the fingers 17, 18 being extended through adjacent holes in the upper row 14 of apertures, and the U-shaped heel or base portion 19 being inserted through an aperture in the lower row 15. The coil portions 21 will be received within the confines of the outwardly directed collar head portion 13, as shown in Figs. 6 and 7.

The angle that the fingers 17, 18 make with the plane in which the heel or base portion 19 lies is such that the fingers 17, 18 and base portion 19 cannot be mounted through the rows 14, 15 of apertures unless the fingers and base portion are bent toward each other. Such bending can take place without difficulty, in view of the spring-like characteristics of the coils 21 interconnecting the base portion to the fingers. The fingers 17, 18 and base portion 19 are folded toward each other, and the fingers themselves moved towards a position in which their outer portions 23 are substantially parallel to each other, which enables the fingers of each element to be placed through adjacent apertures in the top row 14 of holes, and the base portion 19 to pass through an intermediate aperture in the

lower row 15 of holes. Thereafter, the folding force imposed on the element 16 is released, which allows the fingers 17, 18 to spring back to their initial divergent relationship and the coils 21 to unwind; so as to increase the angle between the plane of the fingers 17, 18 and the plane of the base portion 19. When the scratcher element 16 reassumes its initial shape and condition, it cannot move back out through the apertures 14, 15, inasmuch as the depending heel or base portion 19 will engage the collar or sleeve 10 below the lower aperture 15, and the inner portions 22 of the fingers 17, 18 engage the collar or sleeve above the upper apertures 14. When the fingers and base portions reassume their initial position, the coils 21 are confined entirely within the bead portion 13 of the collar; so as not to project within the inner cylindrical wall of the latter, which might cause interference with the relative sliding of the casing B within the collar 10.

As disclosed in the drawings, the heel portion 19 of each scratcher element extends downwardly through its own individual lower aperture 15. However, each finger 17 of a scratcher element shares an upper aperture 14 with a finger 18 of the next adjacent scratcher. Thus, as is evident from Fig. 5, one scratcher element 16 is inserted through the adjacent apertures 14 and the intermediate aperture 15, and the next adjacent scratcher element is mounted in place in the collar, with its base portion 19 extending through an adjacent aperture 15 of a lower row. The spring finger 18 at one side of the element extends through the same aperture 14 as the spring finger 17 of an adjacent scratcher element. Inasmuch as the fingers 17, 18 of each element diverge from one another, the spring fingers extending through the aperture overlap or cross one another, as is readily apparent from a consideration of Figs. 2 and 5. One finger 17 will engage another finger 18 of the next element 16, causing the fingers to mutually support one another. As a matter of fact, depending upon the extent of divergence of the fingers 17, 18 of each scratcher element, one finger 17 may overlap several fingers 18 of other scratcher elements, making the construction much stronger.

After the finger elements 17, 18 and base portions 19 are assembled through the apertures 14, 15 within the collar 10, and the fingers and base portions allowed to reassume their initial positions, it is preferred that each spring element be permitted to oscillate to a certain extent about the axis of the coils 21, before the fingers 17, 18 engage the collar material above the upper row 14 of apertures, or the base portions 19 engage the collar material below the lower row 15 of apertures. This ability of each scratcher element 16 to swing upwardly and downwardly allows the spring fingers 17, 18 to swing upwardly to a certain extent during downward movement of the scratcher element in the well bore (see full line position in Fig. 6), decreasing the force with which the fingers engage the mud cake or sheath C on the wall of the well bore D, during descent of the apparatus therewithin (Fig. 3).

It is desirable to have very little, if any, scratching or scraping of the fingers 17, 18 on the wall of the well bore during lowering of the casing. However, upon moving the casing upwardly, the spring fingers 17, 18 tend to move from the full line position shown in Fig. 7 to the dotted line position. During such movement, the heel portion 19 is first engaged with the collar material 75 below the lower aperture 15, which causes the

heel, in effect, to serve as an anchor for the coil springs 21. Thereafter, the casing B is elevated and the spring elements 16 are moved downwardly to the dotted line position shown in Fig. 7, the coil springs 21 being wound or unwound (as the case may be, depending upon the direction in which the coils are wound) to allow the fingers 17, 18 to assume the dotted line position and to also impose a spring force tending to return them to their initial upper position. While the springs are in the dotted line position, they will engage the mud cake or sheath C on the wall of the well bore D with substantial force, scratching and scraping this mud cake from the wall, allowing circulating fluid pumped down the casing string B to flush the particles of mud cake removed by the scratcher elements 16 to the top of the hole (Fig. 4).

By reciprocating the casing B through the desired distance in the well bore D the required number of times, substantially all of the mud cake C can be removed from the wall of the hole along the distance traversed by the scratcher A, insuring a proper bond between cementitious material, placed behind the casing, with the formation, and insuring against subsequent channeling through the hardened cementitious material.

As disclosed in the drawings, and particularly Figs. 5 and 9, a large number of turns can be provided in each spring coil portion 21. As a matter of fact, the coils of the spring elements may be placed closely adjacent one another; so as to substantially completely fill the circumference around the bead 13. There is nothing else disposed in the bead to interfere with the coils, which allows a maximum number of turns to be used, if desired. It is to be understood, however, that the number of turns can be varied, depending upon the spring force required in the fingers 17, 18 during the scraping operation.

By virtue of the disposition of the spring coils 21 adjacent one another around the interior of the collar bead 13, one coil can abut and support the adjacent coil of another scratcher element, which assists in holding the springs in proper assembled relation within the collar 10. For that matter, it is to be noted that the elements 16 can only move arcuately to a very small extent with respect to the collar 10, since the arms 20 of the U-shaped base member will engage the side walls of the lower apertures 15. In addition, the inner finger portions 22 will also engage the side walls of the upper apertures 14, to limit the extent of arcuate movement of each spring element 16 within the collar or sleeve 10. As stated above, the reassuming of their initial shape by the fingers 17, 18 and base portion 19, after insertion through the apertures 14, 15, precludes the spring elements 16 from moving inwardly of the collar 10. In this connection, any tendency to move inwardly is prevented by the engagement of the periphery of the casing section B with the spring coils 21.

The scratcher device A may be made with a single set of springs 16, or a plurality of sets may be embodied in a single collar or sleeve 10. In the form disclosed in the drawings, the sleeve is of sufficient length to accommodate two circumferential beads 13, and two sets of spring scratcher elements 16 mounted therein. It is preferred to offset the lower set of spring elements 16 with respect to the upper set; so that a greater circumferential extent of the wall of

the well bore D is scratched during reciprocation of the apparatus within the well bore.

The collar or sleeve 10 may consist of a circumferentially continuous, generally cylindrical member adapted to be slipped longitudinally over the end of the casing section B and into appropriate position, after which the stop elements or rings 11, 12 may be welded, or otherwise suitably secured, to the casing section on opposite sides of the scratcher device. However, the collar or sleeve 10 may be sectionalized, to facilitate assembly on the casing section by bringing sleeve segments laterally of the casing to a position around the casing section B. As shown in the drawings, the collar may be formed of two sections 10a, 10b having hinge knuckles 30, 31 formed at their confronting end portions, which interleave with one another. Following placing of the sections 10a, 10b about the casing section B, with the spring elements 16, of course, already mounted in each collar section, suitable hinge pins 32, or other fastening elements, may be disposed through the interleaved knuckles 30, 31 on diametrically opposite sides of the scratcher device A, thereby firmly attaching the collar sections 10a, 10b to one another, and, in effect, constituting them as a continuous cylindrical member 10.

It is, accordingly, apparent that a scratcher device has been provided which is made from a minimum number of parts. In fact, it consists essentially of the collar or supporting member 10 and the scratcher elements 16 themselves, and nothing else. The design lends itself to the automatic formation of the scratcher elements 16, and their insertion through the apertures 14, 15 in the collar by automatic equipment, the various elements being properly oriented with respect to each other, resulting in the production of a complete scratcher device A. The lack of any other objects or materials within the collar bead or beads 13 makes it possible to place more spring coils 21 in each element 16, which enhances the flexibility of the spring elements and renders them less susceptible to permanent distortion during reciprocation of the device in the well bore in the performance of the scratching function. A large spring force is available during upward movement of the scratcher to remove the mud cake or sheath C from the wall of the well bore; whereas, the spring fingers 17, 18 can readily fold upwardly against comparatively little resistance, to preclude the imposition of a large scratching force on the mud sheath C during downward movement of the casing string B in the well bore D. In this manner, the mud sheath remains intact during lowering of the apparatus in the well bore, and it is only upon elevation of the casing string to substantial extents, which is done purposely, that the scratching elements 16 are effective to remove the mud sheath from the well bore wall.

The inventor claims:

1. In a wall scratcher: a supporting member having an outwardly directed bead provided with a plurality of spaced apertures; a plurality of spring elements, each element including a finger extending outwardly through one aperture, a heel portion extending outwardly through another aperture, and a coil spring portion interconnecting said finger and heel portion and disposed within said bead.
2. In a wall scratcher: a supporting member having an outwardly directed bead provided with a plurality of spaced apertures; a plurality of

spring elements; each element including a pair of spaced fingers, each finger extending outwardly through a different aperture, a heel portion extending outwardly through an aperture between the apertures through which said pair of fingers extends, and a coil spring portion within said bead interconnecting said heel portion and each finger.

3. In a wall scratcher: a generally cylindrical collar having a circumferential outwardly directed bead provided with a plurality of longitudinally spaced rows of apertures extending circumferentially around said bead, the apertures of one row being circumferentially offset with respect to the apertures of another row; a plurality of spring elements having fingers extending outwardly through the apertures of one row and heel portions extending outwardly through the apertures of another row, said heel portions being contactable with the exterior of said collar, each spring element having an intermediate coil spring portion disposed within said bead and interconnecting said finger and heel portion.

4. In a wall scratcher: a generally cylindrical member having a circumferential outwardly directed bead provided with a plurality of upper and lower rows of apertures extending circumferentially around said bead, the apertures of the upper row being circumferentially offset with respect to the apertures of the lower row, a plurality of spring elements having fingers extending outwardly through the apertures of the upper row and heel portions extending outwardly through the apertures of the lower row, said heel portions being contactable with the exterior of said collar, each spring element having an intermediate coil spring portion disposed within said bead and interconnecting said finger and heel portion.

5. In a wall scratcher: a generally cylindrical collar having a circumferential outwardly directed bead provided with a plurality of longitudinally spaced rows of apertures extending circumferentially around said bead, the apertures of one row being circumferentially offset with respect to the apertures of another row; a plurality of spring elements; each element including a pair of spaced fingers, each finger extending outwardly through a different aperture of one of said rows, a heel portion extending outwardly through an aperture of another of said rows, said heel portion being contactable with the exterior of said collar, and an intermediate coil spring portion disposed within said bead and interconnecting heel portion with each of said fingers.

6. In a wall scratcher: a generally cylindrical member having a circumferential outwardly directed bead provided with upper and lower rows of apertures extending circumferentially around said bead, the apertures of said upper row being circumferentially offset with respect to the apertures of said lower row; a plurality of spring elements; each element including a pair of spring fingers, each finger extending outwardly through a different aperture of said upper row, a heel portion extending outwardly through an aperture of said lower row, and an intermediate coil spring portion disposed within said bead and interconnecting said heel portion with each finger.

7. In a wall scratcher adapted to be mounted on a running-in string to be disposed in a well bore: a supporting member having a plurality of spaced apertures; a plurality of spring elements, each element including a finger extending outwardly through an aperture, a heel portion extending outwardly through another aperture

and alongside said member and contactable with said member, whereby said heel portion will substantially overlap the exterior surface of said member, and an intermediate portion interconnecting said finger and heel portion and disposed within said member; said supporting member having a portion abutting said intermediate portion to prevent bodily movement of said spring element along said supporting member.

8. In a wall scratcher adapted to be mounted on a running-in string to be disposed in a well bore: a supporting member having a plurality of spaced apertures; a plurality of spring elements, each element including a finger extending outwardly through an aperture, a heel portion extending outwardly through another aperture and alongside said member and contactable with said member, whereby said heel portion will substantially overlap the exterior surface of said member, and a coil spring portion interconnecting said finger and heel portion and disposed within said member; said supporting member having a portion abutting and embracing said coil spring portion to prevent bodily movement of said spring element along said supporting member.

9. In a wall scratcher adapted to be disposed in a well bore: a supporting member having a plurality of longitudinally spaced rows of apertures, the apertures of one row being offset with respect to the apertures of another row; a plurality of spring elements, each element including a finger extending outwardly through an aperture of one row, a heel portion extending outwardly through an aperture of another row and alongside said member and contactable with said member, whereby said heel portion will substantially overlap the exterior surface of said member, and an intermediate portion interconnecting said finger and heel portion and disposed within said member; said supporting member having a portion abutting said intermediate portion to prevent bodily movement of said spring element along said supporting member.

10. In a wall scratcher adapted to be mounted on a running-in string to be disposed in a well bore: a supporting member having a plurality of spaced apertures; a plurality of spring elements, each element including a pair of spaced fingers, each finger extending through a different aperture, a heel portion extending outwardly through an aperture between the apertures through which said pair of fingers extend and alongside said member and contactable with said member, whereby said heel portion will substantially overlap the exterior surface of said member, and intermediate portions interconnecting said fingers and heel portion and disposed within said member; said supporting member having a portion abutting said intermediate portions to prevent bodily movement of said spring element along said supporting member.

11. In a wall scratcher adapted to be mounted on a running-in string to be disposed in a well bore: a supporting member having a plurality of spaced apertures; a plurality of spring elements, each element including a pair of spaced fingers, each finger extending through a different aperture, a heel portion extending outwardly through an aperture between the apertures through which said pair of fingers extend and alongside said member and contactable with said member, whereby said heel portion will substantially overlap the exterior surface of said member, and coil spring portions interconnecting said

fingers and heel portion and disposed within said member; said supporting member having a portion abutting and embracing said coil spring portions to prevent bodily movement of said spring element along said supporting member.

12. In a wall scratcher adapted to be disposed in a well bore: a supporting member having a plurality of longitudinally spaced rows of apertures, the apertures of one row being offset with respect to the apertures of another row; a plurality of spring elements, each element including a pair of spaced fingers, each finger extending through a different aperture of one row, a heel portion extending outwardly through an aperture of another row and alongside said member and contactable with said member, whereby said heel portion will substantially overlap the exterior surface of said member, and intermediate portions interconnecting said fingers and heel portion and disposed within said member, said supporting member having a portion abutting said intermediate portions to prevent bodily movement of said spring element along said supporting member.

13. In a wall scratcher adapted to be disposed in a well bore: a supporting member having a plurality of longitudinally spaced rows of apertures, the apertures of one row being offset with respect to the apertures of another row; a plu-

rality of spring elements, each element including a pair of spaced fingers, each finger extending through a different aperture of one row, a heel portion extending outwardly through an aperture of another row and alongside said member and contactable with said member, whereby said heel portion will substantially overlap the exterior surface of said member, and coil spring portions interconnecting said fingers and heel portion and disposed within said member; said supporting member having a portion abutting and embracing said coil spring portions to prevent bodily movement of said spring element along said supporting member.
